UNITED STATES PATENT OFFICE.

HENRY H. FEFELL, OF DAYTON, OHIO, ASSIGNOR TO OHMER FARE REGISTER COMPANY, OF DAYTON, OHIO, A CORPORATION OF NEW YORK.

FARE-BOX.

1,142,244.

Specification of Letters Patent.

Patented June 8, 1915.

Application filed May 25, 1914. Serial No. 840,699.

To all whom it may concern:

Be it known that I, HENRY H. FEFELL, a citizen of the United States, residing at Dayton, in the county of Montgomery and State of Ohio, have invented certain new and useful Improvements in Fare-Boxes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in fare boxes for the collection of fares in street cars, etc.

The primary object of the invention is to provide a device of this type so constructed 20 and arranged that the fare receptacle cannot be inserted in the box unless the lid of the receptacle is open, and in which the lid of the receptacle is closed and locked when said receptacle is withdrawn from the box.

25 This arrangement prevents persons having access to the fares after they have been deposited and from appropriating them or making such subsequent use of them as will deprive the company of its revenue.

30 Incidental to the above accomplishments, other objects and advantages are attained as will more fully appear hereinafter.

To the above ends the device is simple in construction and efficient in operation and 35 possesses the features hereinafter described.

Referring to the accompanying drawings, Figure 1, is a front elevation of my improved fare box; Fig. 2 is a section thereof on the line *a—a* of Fig. 1; Fig. 3 is a section 40 thereof on the line *b—b* of Fig. 2; Fig. 4 is a section on the line *d—d* of Fig. 5 showing the receptacle in the act of being withdrawn from the box; Fig. 5 is a section on the line *c—c* of Fig. 4; Fig. 6 is a perspective view 45 of the fare receptacle; Fig. 7 is a detail perspective view of the ratchet disk constituting one of the locking members for the lid of the fare receptacle; and Fig. 8 is a side elevation of the lower end of the fare box.

50 In the specification and drawings, similar reference characters indicate corresponding parts.

Referring more particularly to the drawings, 1 represents an upright cylinder or casing which may be mounted on a suitable

standard (not shown) in a suitable place at the entrance of a car. Mounted on the top of the cylinder 1 is a ring 2 in which a shaft 3 is journaled and on said shaft is mounted a tilting table 4 which is tilted by a lever 5 mounted on one end of the shaft 3 on the outside of the cylinder 1; see Fig. 1. The table 4 is under the influence of a spring 6 mounted on the shaft 3 while a stop 7 is provided at a suitable point to hold the table in a horizontal position against the tension of the spring. The fares, either paper or money, fall upon said table as they are deposited through an initial receiver of any well known type such as the following: 70 Mounted on the ring 2 is a glass cylinder 8 through which the fares may be viewed on the table 4 and mounted on the upper end of the cylinder 8 is a mouth-piece 9 provided with an opening 10 through which the fares are deposited in said receiver. The receiver is provided with a series of baffle or guide plates 11 which are well known and instrumental in preventing the subsequent withdrawal or removal of the fares from 75 said receiver. The said cylinder 8 and the mouth piece 9 are held in position on the ring 2 by vertical bars 12 which extend between the ring and the mouth piece. After the fares have been deposited in the receiver 80 8 and have been viewed by the conductor to ascertain their genuineness, the said fares may be deposited in a final repository or receptacle 13 mounted below the table 4 by 85 actuating the lever 5 to tilt the table 4. The receptacle 13 is cylindrical and fits snugly in the bottom of cylinder 1, and the same is provided with a bottom 14 and a lid 15, the latter being pivoted on the shaft 16 mounted in the sides of said receptacle 13. The 90 lid 15 is provided with a spring-lock 17 which co-operates with a lug 18 on the receptacle 13 in locking the lid in its closed position. The lock 17 snaps automatically when the lid is closed. The said lid 15 is provided with a spring 19 which exerts an influence to open and to hold said lid in an opened position; and said lid is further provided with a ratchet disk 20 having a shoulder 21 and which is mounted on the shaft 16. The 95 said ratchet disk 20 moves at all times with the lid 15 and is secured to said lid through the agency of a pin 22 which extends through the lid and the hub 23 of the disk. The shoulder 21 of the ratchet disk 20 is 100 105 110

adapted to be engaged by the nose 24 of a pawl 25 pivoted at 26 to a bracket 27, said bracket being supported on the interior of the cylinder 1. The pawl 25 is provided 5 with a spring 28 which normally draws upon said pawl. The lid 15 is further provided with an opening 29 through which the ratchet disk 20 projects and which also receives the nose 24 of the pawl 25 when the 10 said nose is in engagement with the shoulder 21 of said disk.

The final receptacle 13 may be supported and held in the cylinder 1 by any well known means, or by a bottom 30 hinged 15 at 31 and provided with a hasp 32 to receive a padlock 33. To aline the receptacle 13 so that the nose 24 of the pawl 25 will enter the opening 29 in the lid 15 when the receptacle 13 is placed in the 20 cylinder 1, the said receptacle 13 is provided with a pin 34 adapted to be received by a recess 35 in the side of said cylinder. The length of the opening 29 in the lid 15 and the shape of the pawl 25 are such that 25 the receptacle 13 will be prevented from moving to a position which would allow the bottom 30 to be closed unless the lid 15 is first unlocked and in an elevated position, as shown in Fig. 2. This can be clearly 30 understood from Fig. 4, in which the broken horizontal line 36 represents the top of the receptacle 13 when in a position with the bottom 30 closed. When the receptacle 13 is withdrawn, the pawl 25 will rock the lid 35 15 to a horizontal position at which time it will be locked by the spring lock 17. The receptacle 13 is, therefore, locked when it is withdrawn, thereby preventing unauthorized persons gaining possession of the 40 contents or fares. The receptacle can only be opened by authorized persons or those having possession of a key to the lock 17.

Having described my invention, I claim:

1. In a fare box, a casing, a cylindrical 45 fare receptacle mounted in said casing and removable from the bottom thereof, a lid pivotally mounted in the mouth of said receptacle, ratchet devices mounted on the lid and the casing and adapted to close said lid 50 as the receptacle is being withdrawn from the casing, said ratchet devices also preventing the insertion of the receptacle in the casing when the lid is closed, and means for locking said lid when moved to its closed position by said ratchet devices.

2. In a fare box, a casing, a fare receptacle mounted in said casing and removable through the bottom thereof, a lid for said receptacle pivotally mounted at the mouth 60 thereof, a ratchet member attached to said lid, a pawl pivoted to the casing in operative relation with said ratchet member, said ratchet member and said pawl being adapt-

ed to move the lid to a closed position as the receptacle is being withdrawn from the casing, and means on the lid and the receptacle for locking said lid when moved to its closed position by said pawl and ratchet.

3. In a fare box, a casing, a fare receptacle mounted in said casing, a lid for said receptacle pivotally mounted in the mouth thereof, devices adapted to lock said lid when in its closed position, a ratchet member carried by said lid, a pawl mounted on the casing in operative relation with said ratchet 75 member, said ratchet member and pawl being adapted to close the lid as the receptacle is being removed from the casing and to prevent the insertion of said receptacle in said casing when the lid is closed, and means for 80 supporting said receptacle in the casing.

4. In a fare box, a casing, a fare receptacle inserted in said casing, a hinged lid for said receptacle, a spring exerting influence to hold said lid in an opened position, a 85 spring-lock carried by said lid, a ratchet carried by said lid, a pawl in operative relation with said ratchet and adapted to close said lid when the receptacle is withdrawn, said lid being provided with an opening which receives the pawl, the lid at one end of said opening and the pawl coöperating to prevent the insertion of the receptacle when the lid is closed; and means for holding the receptacle in the casing.

5. In a fare box, a casing, a fare receptacle inserted in said casing, a hinged lid for said receptacle, a spring exerting influence to hold said lid in an open position, a spring-controlled lock carried by said lid, a ratchet carried by said lid, a pawl in operative relation with said ratchet and adapted to close said lid when said receptacle is withdrawn, said lid being provided with an opening which receives the end of the pawl, one end 100 of said opening and the pawl coöperating to prevent the insertion of the receptacle when the lid is closed, an alining pin carried by said receptacle, and means for holding said receptacle in the casing.

6. In a fare box, a casing having a hinged bottom, a fare receptacle adapted to be supported on said bottom, a lid for said receptacle fulcrumed at the mouth thereof, a ratchet pivoted upon the axis of said lid, 115 and a pawl pivoted on the casing and adapted to be projected through said lid to engage said ratchet, said pawl and ratchet being adapted to manipulate the lid.

In testimony whereof I affix my signature, 120 in presence of two witnesses.

HENRY H. FEFELL.
